UNITED STATES PATENT OFFICE.

CHARLES SWINSCOE, OF BOSTON, MASSACHUSETTS.

IMPROVEMENT IN STEAM-PUMPS.

Specification forming part of Letters Patent No. 124,639, dated March 12, 1872.

Specification describing an improved arrangement of pumps operated by the piston of a steam-engine, invented by CHARLES SWINSCOE, of Boston, county of Suffolk, Commonwealth of Massachusetts.

My invention relates to the arrangement of two or more pump-pistons or plungers, in combination with the piston of the steam-engine operating the same, in such a manner as to equalize the work done by said steam-piston, whether traveling in one direction or the other, in the steam-cylinder.

In the drawing, I have shown a simple method of accomplishing this result by means of two plunger-pumps, A and B; one pump, A, being arranged like the ordinary plunger-pump, and the other pump, B, being so arranged as to force in the opposite direction from the pump A. This fully illustrates my invention, which consists, generally and broadly, in attaching to the same side of a piston (which is usually the piston of a direct-acting steam-engine) two or more plungers or pistons, by means of appropriate rods or similar connection, the said plungers or pistons being arranged in cylinders and provided with valves to force in opposite directions during the travel of the steam-piston, said cylinders and valves

being arranged in any of the known methods, or by improved methods of my own invention, and forming, when combined with the driving-engine, a new and improved steam-pump, differing essentially from the ordinary double-acting pump, but retaining its effectiveness, while it has also new advantages resulting from its peculiar arrangement. In some cases it is found desirable to use more than two plungers or pistons, and in such case the force and work may be equalized by the relative diameters of the pistons or plungers. Details of arrangement may also differ to accommodate this construction of pump to different work; but—

What I claim is—

Connecting to the same side of a steam-piston two or more pump-pistons or plungers which work in cylinders on the same end of the engine-cylinder, part of said plungers or pistons being arranged to force while traveling in one direction, and the others to force while moving in the opposite direction.

CHARLES SWINSCOE.
